Harry D. Reed,
By their attorney, Willard S. Goodrich

UNITED STATES PATENT OFFICE.

WILLIAM H. GOODRICH, OF CAMPOLLO, AND HARVEY D. REED, OF NORTH ABINGTON,
MASSACHUSETTS.

DIE.

1,279,535.

Specification of Letters Patent. Patented Sept. 24, 1918.

Application filed March 26, 1917. Serial No. 157,356.

To all whom it may concern:

Be it known that we, WILLIAM H. GOODRICH, a citizen of the United States, residing at Campello, in the county of Plymouth and State of Massachusetts, and HARVEY D. REED, a citizen of the United States, residing at North Abington, in the county of Plymouth and State of Massachusetts, have invented new and useful Improvements in Dies, of which the following is a specification.

This invention relates to improvements in dies and particularly to dies adapted to form the soles of boots and shoes.

15 The object of the invention is to provide a die having the form of a sole with a second die mounted within and adjustable transversely of said first named die, adapted to cut from said sole, at the heel portion 20 thereof, the central portion of said heel, said cut out portion constituting the top lift of the heel of the shoe, embodying said sole when the heel thereof is of such a taper (as with the military or French heel) that the 25 top lift is much smaller than the base of the heel or the portion removed from the sole of one shoe, especially a man's shoe, may be used as the top lift on a shoe of smaller size or on a lady's shoe.

30 Another object of the invention is to provide novel means for attaching the inner die to the outer die.

A further object of the invention is to provide supporting means for the stripping devices of both of said dies.

The invention consists in the combination and arrangement of parts set forth in the following specification and particularly pointed out in the claims.

40 Referring to the drawing:

Figure 1 is a plan view of a die embodying our invention.

Fig. 2 is a transverse section taken on the line 2—2 of Fig. 1.

45 Fig. 3 is a detail section taken on the line 3—3 of Fig. 1.

Like numerals refer to like parts throughout the several views of the drawings.

In the drawings, 1 is a die having substan-

tially the form of a shoe sole. The lower 50 edge 2, entirely around said die, is beveled or sharpened to form a cutting edge, while the upper edge 3 thereof is flattened and is the pressure edge of said die. A yoke 4 is disposed transversely of the heel portion 5 55 of said die 1 and is secured to opposite sides of said die, preferably by rivets 6, said yoke being disposed at a distance below the pressure edge 3 of the die. The rivets 6 extend through upwardly extending members 7 60 which terminate flush with the pressure edge 3 of the die and relieve the rivets 6 from the pressure applied thereto during the cutting operation.

A second die 8, preferably having the 65 form of a heel top lift, is provided with a sharpened lower edge 9 which constitutes a cutting edge, said cutting edge 9 terminating in the same plane in which the cutting edge 2 of the outer die terminates. Lugs 10 70 project outwardly from the die 8 and are attached to the yoke 4 preferably by screws 11, which are arranged in holes 12 in said lugs, slightly larger than the screws 11, so as to permit a limited movement of the die 8 75 transversely of the die 1. The projecting portions of the screws 11 above the yoke 4 are provided with nuts 13.

Disposed centrally of the yoke 4, directly above the die 8, is an upwardly projecting 80 member 14 which constitutes a backing for the inner die 8, said member 14 extending upwardly to the plane containing the upper edge of the die 3 and the extension 7 of said yoke, said plane representing the under surface 85 15 of a platen 16 of the press which supplies pressure to the die.

Spaces 17, 17, formed between the member 14 and the members 7, constitute recesses within which the nuts 13 and the projecting portions of the screws are arranged, and enable said screws and nuts to be easily adjusted. A stripper plate 18 is arranged to fit within the lower portion of the die adjacent to the cutting edge thereof and is yieldingly mounted relatively to said cutting edges so that when the die is brought down upon the piece of leather or sheet material 90 95

that is to be cut said stripper will yield under pressure but upon the removal of said pressure will return to its normal position and eject the blank which has been cut by 5 the die.

The mounting for said stripper plate preferably consists of a plurality of brackets 19 at the toe portion of the die, while an extension 20 of the yoke 4 constitutes the brackets 10 for the heel portion thereof. Screws 21, having countersunk heads 22 arranged within the stripper plate 18, extend upwardly in sliding engagement with the brackets 19 and extension 20 and have nuts 23 attached at 15 their upper ends, whereby said stripper plate may be adjusted vertically with respect to the cutting edges of said die.

Spring 24 are interposed between the plate 18 and said brackets and yieldingly 20 retain the plate in its normal position. The plate 18 is recessed at 25 to permit the die 8 to protrude therethrough, said recess being larger than said die so as to permit a transverse adjustment of the die 8 relatively to 25 the die 1.

To serve as a stripper for the die 8 a section of resilient material, preferably rubber 26, is inserted within said die substantially the whole length, abutting against the under 30 side of the yoke 4, said rubber being recessed at 27, 27 to permit the transverse expansion thereof when pressure is applied to the lower end during the cutting of the material.

35 With the construction hereinbefore set forth, it will be possible to utilize the sheet material or leather at the center of the heel portion of the sole, as a top lift for a heel where a good quality of leather is required, 40 while an inexpensive filling will serve just as well to fill the hole so made, and permits said top lift to be cut from the leather simultaneously with the cutting out of the sole, saving labor and giving the top lift 45 the accurate shape for use on the heel.

Furthermore, by providing the adjustments and detachable features of the inner die, different sizes of top lift dies may be attached to the sole dies and said top lift die 50 may be adjusted so as to cut the exact portion desired from the sole.

Having thus specifically described the invention what we claim and desire by Letters Patent to secure is:

55 1. In combination, a die having the form of a shoe sole, a yoke disposed transversely of and within the heel portion of said die and at a distance from the back edge thereof, a second die arranged in a predetermined 60 position upon said yoke, the cutting edges of said dies terminating in the same plane.

2. A cutting die having, in combination, a yoke disposed within and transversely

thereof at a distance from the back edge of said die, a second die attached to said yoke 65 within said first named die, and means for adjustably securing said second die to said yoke.

3. A cutting die having, in combination, a yoke disposed within and transversely of 70 said die at a distance from the upper edge thereof, a second die arranged within said first named die and adjustably secured to said yoke, the cutting edges of said dies terminating substantially in the same plane, 75 and means projecting from said yoke above said second die to the plane of the upper edge of said first named die and constituting a backing for said second named die during the cutting operation. 80

4. In combination, a cutting die having the form of a sole, a yoke disposed within and transversely of said die at a distance from the back edge thereof, a second die having the form of a heel top lift attached 85 to said yoke within said first named die, means for adjusting and securing said second named die to said yoke substantially central relatively to the first named die, and means extending upwardly from opposite 90 ends and the central portion of said yoke to the plane of the back edge of said die and constituting a backing for said yoke during the cutting operation.

5. In combination, a cutting die having 95 the form of a sole, a yoke arranged transversely of the heel portion of said die, a second die having the form of a heel top lift adjustably and detachably mounted upon said yoke substantially centrally with 100 respect to said first named die, and a stripper plate yieldingly mounted within said first named die, said stripper plate having a recess coinciding with the shape of said second die and resilient means arranged 105 within said second die and constituting a stripper for said die.

6. In combination, a cutting die having the form of a sole, a yoke disposed within and transversely of said die, a second die 110 arranged within said first named die with its cutting edge terminating in the plane of the cutting edge of said first named die, and screws adapted to adjustably secure said second die to said yoke, said yoke having 115 recesses adapted to receive the projecting portions of said screws.

7. In combination, a cutting die having the form of a sole, a second die detachably mounted substantially central relatively to 120 the heel portion of said sole, the cutting edges of said dies terminating substantially in the same plane, a stripper plate arranged within said first named die, said stripper plate having a recess adapted to permit the 125 cutting edge of said second die to protrude

therethrough, a series of brackets secured to the inner wall of said first named die, screws extending through said stripper plate and having slidable engagement with said brackets, and springs interposed between said stripper plate and each of said brackets, adapted to yieldingly maintain said stripper plate in its operative position relatively to the cutting edges of said die.

5 10 In testimony whereof we have hereunto

set our hands, each in presence of two subscribing witnesses.

WILLIAM H. GOODRICH.
HARVEY D. REED.
